UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

VERTICAL RETORT WITH CROSSOVERS

Application filed August 26, 1924. Serial No. 734,164.

This invention contemplates certain improvements in the art of coking retorts broadly, but in its more specific aspects relates to an improved manner of applying 5 the crossover principle disclosed in my prior Patent No. 1,374,546, granted April 12, 1921, to retorts of the vertical type, such as those of the continuous vertical or those of the intermittent vertical type.

10 In retorts of the continuous vertical type, in which the fuel gases burn at one time in one group of flued walls while another group serves to discharge the products of combustion, it has heretofore been considered necessary to carry the products of combustion from the first group to the second around 15 the coking chambers in order not to interfere with the charging openings in the top of the oven.

20 In the present invention the passageways around the coking chambers are entirely eliminated by the provision of a bridge piece, or bridge pieces, provided with a passageway or passageways across the feed opening 25 for the transfer of the products of combustion. By this arrangement the coal feed from the hopper is split, but this causes no serious difficulty and the arrangement affords a very simple method of transferring 30 the products of combustion and has the distinct advantage that the gases stay within the region of the heating elements of the structure and are not carried outside to heat unnecessary parts. This results in a perfect 35 structural symmetry eliminating tortuous passageways and thereby insuring a more uniform heating.

In batteries of this type it is obvious that 40 alternate coking chambers will be provided with crossovers, whereas the intermediate coking chambers will not be provided with crossovers. The provision of bridge pieces for the crossovers in the former would therefore result in different radiating and heat retaining conditions from those obtaining in 45 the latter. In order to make the conditions uniform in all of the coking chambers I therefore prefer to provide in the latter chambers bridge pieces of similar characteristics to 50 those employed in the former, but not neces-

sarily provided with crossover passageways. This has the distinct advantage that it prevents radiation and retains the heat of the intermediate chambers in addition to rendering the action of all of the chambers uniform, increasing the efficiency and simplifying the 55 operation of the battery.

It is apparent that all of the flues of a given wall will pass the gases in the same direction with the result that there will be no counterflow between adjacent flues of the same wall and all of the flues of each heating wall will be either simultaneously burning or simultaneously operating as downflow flues carrying away the waste gases to outflow 60 operating regenerators.

My invention is illustrated as applied to a combination coke retort battery i. e. one adapted for use either with producer gas or oven gas, a battery having these features 70 being more particularly described in my Patent No. 1,416,222, granted May 16, 1922. My present arrangement of the regenerators and connections is such that when producer gas is used those regenerators which are passing waste gases from adjacent pairs of heating walls lie next to each other and are separated from the regenerators passing producer gas by other regenerators passing air, thus 75 preventing the waste of costly producer gas through the walls leading into the regenerators passing waste gas. When oven gas is used the two producer gas regenerators lying between air regenerators may likewise 80 be connected to convey air since the coke oven gas is directly introduced into the flue walls by special ducts and is not ordinarily passed through the regenerators.

These results I prefer to effect by arranging the connections so that a flued heating wall which is conveying the products of combustion downwardly will be next in order to that heating wall of the adjacent pair which is also conveying the products of combustion 90 downwardly on the opposite side of the intervening coking chamber so that the flued walls carrying the products of combustion will alternate by twos with those carrying the burning gases.

My invention further contemplates the re- 100

versal of flow at periodic intervals in a manner well known in this art. The same order of flow between the regenerators and flued walls is preserved upon reversal but the up-flow flues become down-flow flues and vice versa.

Various other advantages inherently resulting from my construction will be apparent upon consideration of the detailed disclosure.

While the several features of my invention are here described in connection with a particular type of battery I do not wish to be limited to such use since many of the principles involved are obviously applicable to other forms of batteries.

In the accompanying drawings forming a part of this specification and showing, for purposes of exemplification, a preferred form and manner in which the invention may be embodied and practiced but without limiting the claimed invention to such illustrative instance or instances:

Figure 1 is a transverse vertical section of my improved coke oven battery taken on the line 1—1, Fig. 4, showing in section a coking chamber and crossover bridge block, and in dotted lines a regenerator, flued heating wall and communicating passageways.

Figure 2 is a composite horizontal section in different planes on the lines 2A—2A, 2B—2B and 2C—2C of Figure 3 showing the relative arrangement of coking chambers, flued heating walls, regenerators and communicating passageways.

Figure 3 is a transverse vertical section on the line 3—3 of Figure 4, showing in section the flues of a heating wall, one of the pair of associated regenerators and the passageways therebetween.

Figure 4 is a composite longitudinal vertical section in different planes on the lines 4D—4D, 4E—4E and 4F—4F of Figure 3 showing, respectively in section, regenerators, communicating passageways and flued heating walls with crossover disposed about the corresponding coking chamber.

Figure 5 is a top plan view of the oven battery viewed from the line 5G—5G, Figure 4, with the oven hoppers removed, and partly in horizontal section on the line 5H—5H, Figures 1 and 4.

The same characters of references indicate the same parts throughout the several views.

Referring to the drawings—there are illustrated views of a retort battery, or plant, of the by-product type having features above specified; said battery embodies in its construction a plurality of vertically elongated heating walls 11, extending crosswise of the battery, and a plurality of intermediate vertically elongated coking chambers or retorts 12. The heating walls 11 form the side walls of the respective coking chambers 12 as shown more particularly in Figures 2

and 4, and in the present instance are supported by the usual mat and the walls 13 (Fig. 1) which provide a free space below the coking chambers for the travel of the cars which receive the coke after the coking operation is completed. The coal to be coked is charged into the several coking chambers or retorts through charging openings or holes 14 located in the top 15 of the battery and positioned directly above the chambers 12 as shown in Figure 1. Bridging the opening in each alternate coking chamber is a bridge block 15^a provided with a crossover passageway 26 hereinafter referred to. The sides 14^a of the opening 14 I preferably flare outwardly to the sides of the chamber and lead my gas off-takes 16 from the tops of the several chambers through ascension pipes into the usual gas collecting main which carries the distillation gas products to the by-product recovery apparatus. The vertical sides of my bridge block co-operate with the slanting sides of the charging opening to effect an efficient spreading of the coal across the chamber. While I need employ bridge blocks 15^a provided with crossover passageways 26 only above alternate coking chambers, I prefer to employ similar bridge blocks 15^b (Fig. 5) across the intermediate coking chambers for the reason that they serve to retain the heat and render the operation of all of the chambers more uniform. The latter bridge blocks need not be provided with passageways. Above each charging opening 14 I provide a covered feed hopper 14^b and an angled guide 14^c located above the bridge block to direct the charge to the sides thereof. The retort, if of the intermittent type, may be provided at its bottom with a closure 12^d.

Heat for coking the charges of coal in the several chambers 12 is derived from the heating walls 11. As shown in Figures 2 and 3 each heating wall 11 is constituted of a plurality of flame or combustion flues 17 which may be operatively disposed into a single group where the walls are relatively narrow.

The battery structure is extended laterally on one side and vertically elongated regenerators 18 are disposed crosswise of the extended structure having their tops connected to the bottoms of the flues 17 by vertically disposed passageways 23 lying between the regenerators and heating walls and lower horizontal passageways 23¹ with connections to the flues of the respective heating walls. Each regenerator 18 comprises a chamber containing open brickwork commonly called "checkerwork" indicated at 20 and has a distributing sole channel 21 underneath and opening up into such checkerwork, said channel being provided with an outlet 22. The vertical arrangement of the regenerators effects uniform distribution of the gases across the checkerwork and also effects economy of

ground space since the bulk of the regenerators is vertically disposed. The location of the passageways in the wall between the regenerators and heating walls insures 5 against the loss of heat in the transmission of gases from one to the other.

Each flame flue 17 of each heating wall has at its top a port or opening 24 leading into a horizontal bus flue 25, formed in the 10 heating wall, and the bus flues of adjacent walls are communicably connected in pairs, preferably at their middle positions, by passageways 26 formed in the respective bridge blocks 15^a. This arrangement effects a substantially uniform distribution of heat 15 throughout each wall.

The draft through ports 24 (Figures 2 and 3) may be regulated by means of the usual movable dampers or slide bricks 27 20 positioned in the ordinary way in the bottoms of the horizontal flues 25 and adapted to be reached by access flues 28 which extend from the top of the horizontal flues 25 in each heating wall through the top 15 of the 25 battery, there being an access flue positioned over each flame or combustion flue of each heating wall. Extending crosswise of the battery and located beneath each heating wall 11 is a channel 29 for supplying coke 30 oven gas to the several flame flues through ducts 31 provided with the usual nozzles 32. Suitable means is provided for admitting or cutting off the supply of coke oven gas or 35 producer gas dependent upon which it is desired to employ.

The regenerators are arranged in pairs P and A and W and W respectively, as shown in Figure 2, the respective pairs being heated in alternation by the hot combustion products drawn off from the flame or combustion flues and they in turn impart such heat to the medium that they feed into the flame flues. The flow through the respective pairs of regenerators is maintained concurrently in opposite directions as indicated in Figure 2, in which the dots represent up-flow and the crosses down-flow. For example—when there is an up-flow of producer gas in one regenerator P and of air through the other regenerator A of a given pair there will be concurrently a down-flow of the products of combustion through the adjacent pair of regenerators W, W. Moreover, I arrange my connections so that a pair of down-flow regenerators cooperating with a given pair of up-flow regenerators will be adjacent a pair of down-flow regenerators cooperating with a next pair of up-flow regenerators and the connections to the up-flow regenerators are such that the regenerators carrying air will lie between the regenerators carrying producer gas and those carrying the waste gases so that the loss of producer gas by leakage through the walls into the waste gas regenerators is 60 prevented. In other words, as specifically

embodied, my preferred arrangement would comprise two consecutive pairs of down-flow regenerators carrying waste gas followed by one of a pair of up-flow regenerators carrying air followed in turn by two up-flow regenerators of adjacent pairs carrying producer gas and in turn followed by an up-flow regenerator carrying air and continuing throughout the series of regenerators constituting the battery. When oven gas is employed the two producer gas regenerators lying between the air regenerators may be connected to convey air.

It will be apparent that the entire series of flame flues 17 of each heating wall 11 is either operating for down-flow to convey waste products to one set of regenerators, or for up-flow of the burning gases which have previously passed through the other set of regenerators, and further, for alternate coking chambers the flow will be up on one side and down on the other, whereas, for the intermediate chambers flow will be down on both sides or up on both sides in alternation.

Reversal is effected at the end of an operating period determined by practice and by means of any preferred type of reversing mechanism of known form. The regenerators that prior to the reversal operated as inflow regenerators become outflow regenerators, and the outflow operating regenerators become inflow operating regenerators. The up burning series of flue switches function with the down burning series of flues and the supply of gas is turned off from the previously up burning flues and turned on into the mains of the previously down burning flues.

If it be desired to combine coke oven gas as a fuel with a neutral gaseous diluent to the up burning flues, this may be accomplished by diverting a portion of the burnt gases into the two regenerators that previously served for producer gas. The admission into each of the up-burning flues of a supply of the neutral gaseous diluent, such as waste gas, is effective to lengthen greatly the flames within such flues and to prevent the localization of the hottest flame temperature in the extreme lower portions of the flues.

As applied to the intermittent type of vertical retort my improvements permit the designing of the battery for a one-stage heating operation capable of effecting the complete coking of the entire mass before discharging, thus obviating any sticking of a plastic mass due to imperfect coking of portions thereof.

In the horizontal oven the top of the coking chamber is relatively long and therefore a plurality of charging openings are provided along its length to effect an adequate distribution of the coal in charging. The portions of the top between the openings afford convenient means for accommodating

the crossover passageways. In the vertical retort, on the other hand, the top of the coking chamber is relatively short and only a single charging opening is ordinarily employed. This affords no means for accommodating a crossover passageway and therefore vertical retorts heretofore have not been equipped with communicating passageways of this type. My invention, by providing a special bridge piece or bridge block spanning the single charging opening of a coking chamber in vertical retorts, not only accomplishes the result that a means is afforded in retorts of this type for carrying a crossover passageway with the advantages enumerated above but it has among other advantages the further advantage that the single stream of relatively cold coal in its descent during charging substantially surrounds the bridge piece and by reason of its intimate contact therewith maintains the temperature of the latter below the critical or maximum permissible temperature. This is important because the bridge piece is subjected both to the heat of the coking chamber and to that of the hot gases in their passage from the wall confining burning gases to the wall conveying the products of combustion. There results from this heat transfer also the reciprocal advantage that the preheating of the coal facilitates the subsequent coking operation, decreasing the heat losses and increasing the efficiency of the retort.

In intermittent vertical retorts while the flow of the gases through the bridge piece is preferably continuous the feeding of the coal is not but in continuous vertical retorts the flow of both the coal and the gases is continuous, and in the latter case the benefits of my invention are obtained to a maximum degree.

In order to increase the heat transfer from the bridging means to the descending coal I may employ a plurality of bridge pieces provided with crossovers spanning each charging opening and so arranged as to facilitate to the maximum the transfer of heat, consistent with the design of the battery.

The invention as hereinabove set forth is embodied in a particular form of construction but may be variously embodied within the scope of the claims hereinafter made.

I claim:

1. In a vertical coking retort, in combination; a vertically elongated coking chamber having a charge opening at its top and adapted to be discharged through its bottom; heating walls contiguous to said chamber on two opposite lateral sides thereof and respectively constituted of vertical combustion flues; a horizontal connecting flue in the upper part of each heating wall communicably connected with all the combustion flues of its wall; and a bridge block across said charge

opening provided with a flue communicably connecting the horizontal flues at substantially their central points for passing the combustion products from the flues in one of the heating walls to the flues in the other heating wall, substantially as specified. 70

2. In a vertical coking retort, in combination; a vertically elongated chamber having a charge opening at its top and adapted to be discharged through its bottom; flued heating walls contiguous to said chamber on two opposite lateral sides thereof; a connecting flue in each heating wall communicating with the combustion flues therein; and a bridge block across said charge opening provided with a flue communicably connecting the connecting flues for passing the combustion products from the flues in one of the heating walls to the flues in the other heating wall, substantially as specified. 80

3. In a vertical coking retort, in combination; a vertical chamber provided with a charge opening at its top and adapted to be discharged through its bottom; heating walls contiguous to said chamber on two opposite lateral sides thereof, each respectively provided with a combustion flue; and a bridge member across said charge opening at the top of said chamber and provided with a passageway constituting a means of inter-communication between the flues of said respective walls for the passage of combustion products, substantially as specified. 95

4. In a coking retort, a treating chamber provided at its top with a charge opening having two opposite downwardly and outwardly flaring sides extending toward two opposite sides of the chamber respectively and a bridge block with substantially vertical sides spanning said opening, whereby solid material passing downwardly through said opening will be distributed substantially uniformly at each side of said bridge block, substantially as specified. 100

5. In a vertical coking retort battery, in combination; a series of vertical coking chambers each provided at its top with a charge opening and adapted to be discharged through their bottoms; flued heating walls intermediate said chambers; bridging members provided with crossover passageways spanning the charge openings of alternate chambers at their tops and communicably connecting the flued heating walls in pairs for the passage of combustion products from the flues of one heating wall to the flues of the other heating wall of the pair, and other bridging members of substantially the same size and shape and spanning the openings of the intermediate chambers at their tops, substantially as specified. 110

6. In a coking retort, in combination; a chamber; vertically flued heating walls contiguous thereto and vertically extending regenerators located laterally of and contigu- 120

ous to said chamber and walls and communicably connected directly with the flues of the heating walls only through passages leading from the tops of said regenerators to the bottoms of said flued walls, substantially as specified.

7. The combination defined in claim 6, in which the said passages leading from the tops of the regenerators to the bottoms of the flued walls lie within the retort structure 10 and between said regenerators and flued walls, substantially as specified.

8. The combination defined in claim 6, in which the regenerators are arranged in pairs, 15 each of the pairs communicating with the flues of a different heating wall, substantially as specified.

9. In a vertical coking retort battery adapted to be heated by combustion of combustible gas that requires preheating, in combination: 20 a series of vertical coking chambers adapted to be charged through their tops and to be discharged through their bottoms; flued heating walls between successive chambers, the flues of the respective heating walls being 25 communicably connected with the flues of another heating wall on the opposite side of a coking chamber for the passage of combustion products by duct means extending across the tops of the intervening coking chambers; 30 and regenerators comprising separate regenerators for both combustible gas and for air when operable for inflow, said regenerators communicating with the flues of the respective heating walls.

10. In a vertical coking retort, in combination: a vertical coking chamber provided with a charging opening in its top and adapted to be discharged through its bottom; 40 flued heating walls on opposite sides of said chamber adapted to pass burning gases up one side and products of combustion down the other side of said chamber; a bridge member spanning the charging opening in the top of said chamber and provided with a passageway in communication with the flues in the heating walls on opposite sides of said chamber for conducting hot combustion gases continuously from each of the heating 45 walls to the other heating wall; means for feeding coal to said charging opening so that said coal would descend over and along opposite sides of said bridge member simultaneously, whereby the coal would be preheated by heat from combustion products 50 flowing through said bridge member.

11. In a battery of vertical retorts, in combination: a series of vertical coking chambers each adapted to be charged through their 60 tops and to be discharged through their bottoms; heating walls intermediate said coking chambers and respectively constituted of combustion flues, the flues of the respective heating walls being communicably connected 65 with the flues of another heating wall on the

opposite side of a coking chamber for passage of combustion products by duct means extending over the tops of the intervening vertical coking chambers; reversible means for maintaining combustion in alternation in said heating walls; and reversible regenerators respectively communicably connected with the flues of said heating walls.

12. In combination with a vertical coking chamber adapted to be charged through its top and to be discharged through its bottom, 70 heating walls respectively constituting two opposite side walls of said coking chamber and respectively constituted of vertical combustion flues, the vertical flues of the respective heating walls being communicably connected at their upper ends with the flues of another heating wall on the opposite side of a coking chamber by duct means in a bridge block extending across the top of the intervening coking chamber, reversible means for maintaining combustion in alternation in said heating walls whereby exhaust gas produced by combustion in one heating wall may be drawn off through the other, and reversible regenerators respectively communicably connected with the flues of said heating walls at the lower ends of said flues.

In testimony whereof, I have hereunto set my hand.

JOSEPH BECKER.
